UNITED STATES PATENT OFFICE

127,457

DESIGN FOR AN AMUSEMENT MACHINE CABINET

John F. Meyer, Chicago, Ill., assignor to Exhibit Supply Company, Chicago, Ill., a corporation of Illinois

Application March 3, 1941, Serial No. 99,302

Term of patent 7 years

To all whom it may concern:

Be it known that I, John F. Meyer, a citizen of the United States and a resident of Chicago, in the county of Cook and State of Illinois, have invented a new, original, and ornamental Design for an Amusement Machine Cabinet, of which the following is a specification, reference being had to the accompanying drawing, forming a part thereof, and in which the single figure is a perspective view of an amusement machine cabinet showing my new design.

I claim:

The ornamental design for an amusement machine cabinet, as shown.

JOHN F. MEYER.
